UNITED STATES PATENT OFFICE.

CHARLES D. P. GIBSON, OF JERSEY CITY, NEW JERSEY.

VALVE-GEAR.

SPECIFICATION forming part of Letters Patent No. 655,927, dated August 14, 1900.

Application filed July 18, 1899. Serial No. 724,268. (No model.)

To all whom it may concern:

Be it known that I, CHARLES D. P. GIBSON, a citizen of the United States, residing at Jersey City, in the county of Hudson and State 5 of New Jersey, have invented new and useful Improvements in Valve-Gears, of which the following is a specification.

My invention relates to valve-gear for fluid-pressure motors or engines, and contemplates 10 the provision of a valve-gear which while adapted to permit of an engine being quickly reversed when the engineer so desires is calculated to effectually prevent a casual reverse of said engine.

15 The valve-gear is designed, primarily, for use in the fluid-pressure motor forming the subject-matter of my contemporary application filed May 25, 1899, Serial No. 718,214, and is illustrated and described in said application. It may, however, be used to advantage in various other connections.

The construction and operation of the gear will be fully understood from the following description and claims, when taken in conjunction with the annexed drawings, in which—

Figure 1 is a longitudinal vertical section illustrating my improved valve-gear. Fig. 2 is a plan view of said valve-gear. Figs. 3 30 and 4 are detail enlarged sections taken in the planes indicated by the lines 3 3 and 4 4, respectively, of Fig. 2. Fig. 5 is an enlarged detail section taken through a portion of the valve-gear.

35 In the said drawings similar letters designate corresponding parts in all of the several views, referring to which—

A is the bed of an engine; B, a drive-shaft journaled in standards *a*, rising from the bed 40 and equipped with cranks C; D, rods connected to the cranks C and designed to be connected with pistons, (not shown,) and E rods which are designed to be connected with valves (not shown) for controlling the induction and exduction ports of the cylinders containing the said pistons.

The cranks C are disposed as shown, and hence it is necessary to simultaneously move the pistons to which the rods D are connected 45 in opposite directions. To this end I provide a valve-gear comprising oppositely-disposed eccentrics F on the shaft B, links G, having

straps *b*, receiving the eccentrics, link-blocks H, arranged in the links, and rods I, interposed between and pivotally connected to 55 the link-blocks and valve-rod E. By reason of this gear the valve-rod E will be simultaneously moved in opposite directions, as will also the piston-rod D.

For the purpose of adjusting the links and valves I provide the turn-rod J, which have oppositely-threaded ends arranged in threaded sockets *c d*, pivotally connected to the links G and bed A, respectively, as shown.

In order to enable the engineer to readily 65 reverse the direction of movement of the engine, the reversing mechanism (best shown in Fig. 1) is provided. This mechanism is supported by a shaft *e*, arranged in standards *f*, rising from the bed A, and in the preferred embodiment of the invention comprises arms *g*, loose on the shaft *e* and connected by links *h* on the rods I, collars *i*, fast to the shaft *e* and having shoulders *j*, (see Fig. 5,) designed for the engagement of similar shoulders on the arms *g*, a spacing-collar *k*, loose on the shaft, a lever *l*, fast on the shaft *e*, a lever *m*, loose on the shaft *e* and having an arm *n*, connected to a resilient strap *p*, interposed between the arms *g*, 80 a rod *r*, having a lateral arm *s*, and a link *t*, connecting said arm *s* and the lever *m*. The rod *r* is designed to be connected with a lever or other suitable handle, (not shown,) and when it is moved in the direction indicated by arrow in Fig. 1 and the lever *l* is swung forwardly the lower shoulders *j* of the collars *i* abutting against the lower shoulders of the arms *g* will swing said arms *g* and the rods I upwardly, and thereby raise 90 the blocks H to the upper ends of the links G and reverse the engine. At the same time the lever *m*, by reason of the connection between the same and rod *r*, is swung forward at a greater rate of speed than the lever *l*, 95 and its arm *n* is swung upward faster than the arms *g*, with the result that when said arms *g* reach their uppermost position the resilient strap *p* will be bowed upwardly, and consequently enabled to securely hold the 100 link-blocks H against casual movement from their position at the upper ends of the links G. When, on the other hand, the rod *r* is moved in the direction opposite to that indi-

cated by arrow and the link-blocks H are carried at the lower ends of the links G, the resilient strap will be bowed downwardly, and hence enabled to hold the link-blocks against 5 casual upward movement.

It follows from the foregoing that while the engine may be quickly and easily reversed whenever the engineer so desires there is no liability of said engine being casually reversed, which is an important advantage.

The collars i and arms g are so arranged with respect to each other as to afford lost motion and permit a slight oscillatory movement of the said arms g incident to the reciprocatory movements of the rods I, and for the same reason the arm n is made in two sections, which are connected together after the manner of a swivel, as best shown in Fig. 4.

When desirable, a spring, such as M, may 20 be interposed between the rod r and the bed A for the purpose of assisting in returning the parts to the position shown in Fig. 1, which is the normal running position. Said spring is not, however, essential and may be 25 dispensed with, if desired.

Having thus described my invention, what I claim is—

1. In a valve gear or mechanism, the combination of a valve-rod, an eccentric, a link 30 having a strap receiving the eccentric, a link-block, a rod connecting said block and the valve-rod, two levers of different lengths fulcrumed on a common center; the larger of said levers being connected with the rod between the link-block and the valve-rod, and a resilient connection between said levers, substantially as specified.

2. In a valve gear or mechanism, the combination of a valve-rod, an eccentric, a link 40 having a strap receiving the eccentric, a link-block connected with the valve-rod, and two levers mounted on a common center; one of said levers being connected with the link-block and the other lever being arranged to 45 move faster than the first-named lever and being connected thereto by a resilient device adapted to bow, substantially as specified.

3. In a valve gear or mechanism, the combination of valve-rods, eccentrics, links having straps receiving the eccentrics, link-blocks, rods connecting said blocks and the valve-rods, a suitably-supported shaft, arms mounted on the shaft and connected with said rods, a resilient strap interposed between said 55 arms, a lever on the shaft for rocking the said arms, a smaller lever on the shaft having an arm connected to the resilient strap, and an operating-rod connected to the larger lever and having a lateral arm connected with 60 the smaller lever, substantially as specified.

4. In a valve gear or mechanism, the combination of valve-rods, eccentrics, links having straps receiving the eccentrics, link-blocks, rods connecting said blocks and the 65 valve-rods, a suitably-supported shaft, arms mounted on said shaft and connected with

the latter rods, a resilient strap interposed between said arms, a lever on the shaft for rocking the said arms, a smaller lever fulcrumed on the shaft and having an arm connected to the resilient strap and comprising two sections connected in a swiveled manner, and means for operating the levers, substantially as specified.

5. In a valve gear or mechanism, the combination of a valve-rod, an eccentric, a link having a strap receiving the eccentric, a link-block connected with the valve-rod, a lever connected with the link-block, a second lever, an operating device for rocking the levers, and a connection between the levers whereby the link-block is held against casual movement when moved to either end of the link, substantially as specified.

6. The combination with the link-block of 85 a valve-gear; of a lever for moving the link-block, a second lever arranged to move faster than the first-named lever, and means controlled by the second lever whereby the link-block is held against casual movement when 90 moved to either end of the link of the valve-gear, substantially as specified.

7. The combination with the link-block of a valve-gear; of a lever for moving the link-block, a second lever of less length than the 95 first-named lever; said levers being fulcrumed on a common center, means for rocking the levers, and means controlled by the second lever whereby the link-block is held against casual movement when moved to 100 either end of the link of the valve-gear, substantially as specified.

8. The combination with the link of a valve-gear, and a valve-controlling block fitted to slide therein; of means for quickly moving 105 the block to either end of the link, and a block-controlling device connected to and actuated from the block-moving means for holding the block positively in its set position against either end of the link.

9. The combination with link-blocks of a valve-gear; of a lever, connections between the lever and blocks, a second lever, and means operated by the second lever for holding the blocks against casual movement, 115 substantially as specified.

10. The combination with the link-blocks of a valve-gear; of arms mounted on a shaft and connected with the blocks, an arm mounted on the shaft between the first-named arms, a spring-strap interposed between and connected to the outer arms and also connected to the intermediate arm, and means for moving the intermediate arm faster than the outer arms, substantially as specified.

In testimony whereof I have hereunto set my hand in presence of two subscribing witnesses.
